UNITED STATES PATENT OFFICE.

ELIJAH R. ROBERTS, OF BELLEVUE, PENNSYLVANIA.

ELECTRIC-LAMP GLOWER AND METHOD OF ATTACHING TERMINAL WIRES THERETO.

SPECIFICATION forming part of Letters Patent No. 710,369, dated September 30, 1902.

Application filed April 10, 1902. Serial No. 102,313. (No model.)

To all whom it may concern:

Be it known that I, ELIJAH ROY ROBERTS, a citizen of the United States, and a resident of Bellevue, in the county of Allegheny and State of Pennsylvania, have invented new and useful Improvements in Electric-Lamp Glow-
ers and Methods of Attaching Terminal Wires Thereto, (Case No. 1,046,) of which the following is a specification.

10 My invention relates to electric-lamp glow-
ers which are conductors of electricity only when heated to a comparatively high temper-
ature; and it has for its object to provide tu-
bular glowers of this class with terminal wires
15 by a simple and inexpensive method and so that the resulting product shall be efficient and durable in service.

20 My invention is illustrated in the accom-
panying drawings, in which—
Figure 1 is a side elevation of a glower-
blank and two terminal wires before the said
parts are combined. Fig. 2 is a longitudinal
section of the blank shown in Fig. 1, with the
terminal wires inserted in the ends thereof.
25 Fig. 3 is a view similar to Fig. 2, but illus-
trating a modification. Fig. 4 is a longitudi-
nal sectional view of a completed glower.

30 In the manufacture of electric-lamp glow-
ers of the class above referred to more or less
difficulty has been experienced in so attach-
ing terminal wires to the glowers that the con-
nection may be satisfactory from an electrical
standpoint and also so that the mechanical
union may be durable without an undue ex-
penditure of time and skilled labor.

35 The invention constituting the subject-
matter of this application fulfills all the above
requirements and has been found satisfactory
in practice.

40 In practicing my invention I utilize blanks
of tubular form, such as that indicated at 1
in Fig. 1, and after such blank has become
hard and compact, either by drying in the air
or by both this treatment and subsequent
45 roasting at high temperature, I dip one end
of each terminal wire 2, the diameter of which
is slightly less than the interior diameter of
the glower, into a comparatively thin paste
and then insert this paste-coated end into the
50 end of the blank, as indicated in Fig. 2. This
affords a temporary connection between the
terminal wires and the body or blank 1, which

is sufficiently firm to permit of handling the
device. The paste might obviously be ap-
plied to the interior of the glower-blank in-
stead of to the ends of the terminal wires,
though the application to the terminal wires
will ordinarily be found more convenient in
practice.

55 In case the glower-blank is of such compo-
sition or character as to absorb moisture rap-
idly, and thus act upon the paste so as to in-
terfere with the proper insertion of the ter-
minal wires, the wires may be inserted with-
out a previous application of paste either to
60 them or to the interior of the blank. A tem-
porary joint may then be made by applying
a body 3, of paste or cement, to the end of the
blank and around the wire, as indicated in
Fig. 3.

65 After the parts are assembled, as shown in
either Fig. 2 or Fig. 3, I apply a body of paste
or cement 4 to each end of the glower-body
and the contiguous portion of the terminal
wire, this paste or cement being of like or
70 similar material to that composing the glower-
body and being preferably substantially glob-
ular in form, as indicated, though it may be
given a different form, if desired. The paste
or cement 4 may then be hardened by drying
75 or roasting in a suitable frame.

80 If desired, the body of material 4 may be
applied in two or more layers, which may be
separately roasted, and the layers may be of
different materials or compositions of mate-
85 rials.

85 This method of fastening terminal wires to
glowers is simple and inexpensive, and the
resulting product is, as has already been in-
dicated, durable and efficient in service.

90 I claim as my invention—

1. The method of attaching terminal wires
to a tubular glower-blank, which consists in
inserting the ends of the wires into the ends
of the glower-blank and fastening the same
95 in position by means of paste and then ap-
plying a body of cement to each end of the
glower and the contiguous portion of the ter-
minal wire.

100 2. The method of attaching terminal wires
to a tubular glower-blank, which consists in
inserting the ends of the wires into the ends
of the glower-blank and fastening the same
in position by means of paste and then ap-

plying a globular body of cement to each end of the glower and the contiguous portion of the wire.

3. A tubular glower for electric lamps having terminal wires cemented into the ends thereof and having bodies of cement surrounding the contiguous portions of the glower-body and wires.

4. A tubular glower having terminal wires inserted and cemented into the ends thereof

and globular bodies of cement surrounding the contiguous ends of the glower-body and the wires.

In testimony whereof I have hereunto subscribed my name this 4th day of April, 1902. 15

E. R. ROBERTS.
